CHICK BOX

**Josef W. Reynolds, Charlotte, N. C., assignor to
Old Dominion Box Company, Lynchburg, Va., a
corporation of Virginia**

Application May 31, 1939, Serial No. 276,749

5 Claims. (Cl. 229—6)

This invention relates to a container for shipping young chickens, turkeys and other poultry, the container having spaced ribs formed integral with its cover for supporting the bottom of a superposed box in spaced relation thereto and having locking means between said ribs and said bottom to hold the superposed box in position. In the shipping of animals such as baby chicks, it is necessary to provide boxes with ventilating means in the sides and in the top. It is customary to ship these boxes in a superposed relationship to each other in order to economize on space. When the boxes are stacked one upon the other, care must be taken that the ventilation of the top of the lower box will not be obstructed; therefore, it is necessary to form spaced ribs or platforms integral with the ends of the top so that the bottom of the superposed box may rest thereupon at a substantial distance above the cover, and so that other objects placed on the topmost box during shipment will not interfere with the ventilation of the top of the topmost box. Heretofore, when shipping boxes in this manner, much trouble has been occasioned, due to the fact that the superposed box becomes offset and one end thereof slips off its supporting rib, thereby falling down upon the cover and obstructing the ventilation of the adjacent lower box. To remedy this trouble, a locking means has been provided which will prevent the superposed box from shifting relative to the box therebeneath.

It is another object of this invention to provide a cover for a chick box, which cover is formed from a single blank with downturned rims integral with its lower ends and sides, the downturned end rim portions being bent upwardly again at their lower extremities thereby forming two end layers between which the ends of the downturned side rims can be fastened. By providing end rims of this type, an even and uniform continuous surface is presented on the interior of the lid so that the cover can be easily inserted or removed from the box. Also a uniform surface on the outside of the box cover is present which will add to the attractiveness of the container.

It is a further object of this invention to provide a cover for a chick box of the class described with the aforesaid bent-up end rim portions extending a substantial distance above the top of the cover to form rib supports for a superposed box, and a stiffening member extending laterally of each rib and resting on top of the

cover to give added strength to the ribs and to prevent overturning or collapsing.

Some of the objects of the invention having been stated, other objects will appear as the description proceeds when taken in connection with the accompanying drawings, in which—

Figure 1 is an isometric view showing a pair of chick boxes made in accordance with the invention, one box being supported by the other;

Figure 2 is a longitudinal sectional view taken along the line 2—2 in Figure 1;

Figure 3 is a transverse sectional view taken along the line 3—3 in Figure 1;

Figure 4 is an inverted isometric view of the cover used on the improved chick box;

Figure 5 is an inverted isometric view of the box upon which the cover shown in Figure 4 is adapted to be placed;

Figure 6 is an isometric view of the box when in normal position;

Figure 7 is an isometric view of a fabricated blank from which the cover shown in Figure 4 is adapted to be formed.

Referring more specifically to the drawings, the numeral 10 denotes a box having a bottom 11, end walls 12 and side walls 14. The end walls have integral therewith flaps 15 which are bent inwardly and secured to the interior of the side walls 14 by any suitable means such as staples 16. Partitions 17 and 18 are secured between the side walls and end walls of the box by any suitable means such as staples 19 and 20, respectively. These partitions divide the interior of the box 10 into four compartments which are used for housing live animals such as baby chicks. In order to provide the necessary ventilation within the box, suitable perforations 21, 22, 23 and 24 are provided in members 12, 14, 17 and 18 respectively. Although any suitable material may be used in forming a box of this type, it is preferable in many instances to form the same from corrugated paper with the corrugations in the box running transversely thereof so that the end flaps 15 may be bent at right angles to the corrugations thereby giving added strength to the corners of the box.

A cover 30 is provided for fitting over the upper side of the box 10, shown in Figure 6, said cover being formed from a single sheet of material which is fabricated as shown in Figure 7. This cover comprises a top portion 31 having integral with the sides thereof suitable rim portions 32, said rim portions having flaps 33 integral with each end thereof. The portion 31 also has integral with each end thereof extensions 34 which

are bent to form the end rim of the lid as well as to form a supporting rib which extends substantially above the top surface of the cover.

In the formation of the cover 30, the side portions 32 are bent downwardly along dotted lines 36 (Figures 1 and 7). Then the extensions 34 are bent downwardly along dotted lines 37. With the end and side portions bent downwardly, the end flaps 33 are then bent inwardly at substantially right angles along dotted lines 38 so that the inner face of flaps 33 will be disposed against the exterior of the downturned extensions 34. Then the extensions 34 are again bent upwardly along dotted lines 39 thereby confining the end flaps 33, after which suitable staples 40 and 40a are used to secure the doubled portion of extensions 34 on opposed sides of end flaps 33.

At this stage of the construction, the lid portion 30 has been formed with down-turned side 20 and end rims, but the extensions 34 remain to be further bent so as to form supporting ribs for a superposed box. The next step is to bend the extensions 34 towards each other along lines 41 and again along the dotted lines 42 so that the 25 extremity of these extensions will be ultimately directed downwardly against the top portion 31 of the cover 30. It will be noted that these extensions have wedge shaped portions 44 integral therewith, with notches 44a cut in opposed sides 30 thereof which are adapted to fit into suitable slots 45 in portion 31 of the lid. The length of the slots 45 is slightly less than the overall length of the projections and due to the notches 44a, it is 35 possible to shift the projections slightly longitudinally of the slots and cause the same to be anchored thereto in the manner shown in Figures 2 and 3.

When the blanks are fabricated, they are creased along the dotted lines 36, 37, 38, 39 and 40 41 and 42 so that bending can be more easily accomplished during the construction of the lid. By observing Figure 7, it will be noted that the crease lines 42 do not extend entirely across the extensions 34. At the point where a break occurs 45 in the crease line 42, a tab 46 has been cut in the extension; consequently, when the box is formed and the extensions 34 are bent along lines 42, the tabs 46 will project upwardly above the top of ribs 48 in the manner shown in Figures 1, 2 and 50 3. These tabs 46 are adapted to fit into suitable slots 49 in the bottom of a superposed box 10 (see Figures 2, 3 and 5). It is, therefore seen that when a box is superposed upon another that the superposed box cannot become dislocated 55 from the ribs 48 on the supporting lid, when the two boxes are fixed together.

In order to give added rigidity to the ribs 48, a suitable stiffening tab 52 has been provided in each of the extensions 34. These tabs are bent 60 along the dotted lines 53 toward the interior of the ribs 48 and in such a position that the lower edges of these tabs will be disposed against the top of the cover. This stiffening tab 52 is of especial importance when the rib is called upon to 65 carry a heavy load. Since the upper portion of this tab is also in close proximity to the lower interior portion of the rib 48, any overturning of either of the ribs will be resisted.

In the construction of the lid, the corrugations 70 are preferably lengthwise of the lid as shown in Figure 7 in order to give the desired rigidity and to also cause the flaps 33 and extensions 34 to be bent at right angles to the corrugations. This has been proved to be the most effective and efficient way to construct the cover with a view of

obtaining maximum strength. Also suitable perforations 56 are provided in the top of the box at a point between the ribs 48. These perforations admit air to the interior of the box and since the ribs 48 support a superposed box at a substantial distance above these perforations, the flow of air is not materially obstructed.

The interior of the box lid, as well as the exterior, is constructed with a uniform surface. The end tabs 33 do not appear on the outside or 10 on the inside of the box, consequently when using the lid there is no obstruction which would prevent easy insertion or removal. By concealing the tabs 33 from exterior view, a neater box is provided and it is also possible to provide the 15 supporting ribs by extending portions 34 which form interior and exterior covers for the flaps 33.

In the drawings and specification, there has been set forth a preferred embodiment of the invention, and although specific terms are employed they are used in a generic and descriptive sense only and not for purposes of limitation, the scope of the invention being set forth in the appended claims.

I claim:

1. In a container for shipping live baby chicks and the like, a box portion and a lid portion adapted to telescopically fit over the box portion, the lid portion having down-turned sidewalls and down-turned end walls, the sidewalls having flaps extending from each end thereof and bent inwardly against the downturned ends of the lid portion, the downturned ends of the lid portion being doubled upon themselves to confine the flaps of the sidewalls therebetween and projecting upwardly a substantial distance above the upper surface of the lid portion and then projecting inwardly in a horizontal direction and then downwardly, and having portions thereof of penetrating the main lid portion for forming 40 supporting bridges on each end of the lid portion for supporting a similar box disposed in superposed relation to the first box.

2. In a container for shipping live baby chicks and the like, a box portion and a lid portion adapted to telescopically fit over the box portion, 45 the lid portion having downturned sidewalls and downturned end walls, the sidewalls having flaps extending from each end thereof and bent inwardly against the downturned ends of the lid portion, the downturned ends of the lid portion being doubled upon themselves to confine therebetween the flaps on the sidewall portions and projecting upwardly a substantial distance above the upper surface of the lid portion and then 50 projecting inwardly in a horizontal direction and then downwardly and having projections penetrating the main lid portion for forming supporting bridges on each end of the lid portion for supporting a similar box disposed in superposed relation to the first box, said bridge portions having each an upwardly projecting tab and the bottom of each box having slots therein for receiving said upwardly projecting tabs to prevent longitudinal and lateral relative movement between 55 the two boxes when the two boxes are stacked one upon the other.

3. In a container for shipping live baby chicks and the like, a box portion and a lid portion adapted to telescopically fit over the box portion, 70 the lid portion having downturned sidewalls and downturned end walls, the sidewalls having flaps extending from each end thereof and bent inwardly against the downturned ends of the lid portion, the downturned ends of the lid portion 75

being doubled upon themselves to confine the flaps on the end walls therebetween and projecting upwardly a substantial distance above the upper surface of the lid portion and then projecting inwardly in a horizontal direction and then downwardly and having portions thereof penetrating the main lid portion for forming supporting bridges on each end of the lid portion for supporting a similar box disposed in superposed relation to the first box, said bridge portions having each an upwardly projecting tab and the bottom of each box having slots therein for receiving said upwardly projecting tabs to prevent longitudinal and lateral movement between the two boxes when the two boxes are stacked one upon the other, the downturned portion of said flap which is adapted to rest against the upper side of the lid having a scored portion adapted to be bent inwardly to interiorly support the upper surface of the bridge portion.

4. In a chick box, the combination of a bottom structure including side walls and end walls, and a top adapted to telescopically fit over the bottom structure, the top having end walls and side walls, the side walls having tabs extending from each end thereof adapted to be folded against the end walls, the end wall portions being of sufficient length to be folded upon themselves to form the end walls of double thickness to confine the tabs of the sidewalls therebetween and also being of sufficient length to be directed upwardly, then horizontally and

then downwardly against the upper edge of the top and means for securing the end of the said folded end portion to the upper surface of the box top to provide a pair of spaced transversely disposed ribs at each end of the top for supporting another similar box on said ribs.

5. In a chick box, the combination of a bottom structure including side walls and end walls, and a top having sidewalls and end walls to telescopically fit over the bottom structure, the top having end walls and side walls, the side walls having tabs extending from each end thereof adapted to be folded against the end walls, the end wall portions being of sufficient length to be folded upon themselves to form the end walls of double thickness to confine the tabs of the sidewalls therebetween and also being of sufficient length to be directed upwardly, then horizontally and then downwardly against the upper edge of the top and means for securing the end of the said downwardly extending folded end portion to the upper surface of the box top to provide a pair of spaced transversely disposed ribs at each end of the top for supporting another similar box on said ribs, the said similar box having a plurality of holes in its bottom and said ribs having upwardly extending projections adapted to fit into said holes when two of said boxes are disposed in superposed relation to each other.

JOSEF W. REYNOLDS.
